UNITED STATES PATENT OFFICE.

ROY CROSS, OF KANSAS CITY, MISSOURI, ASSIGNOR TO CROSS DEVELOPMENT CORPORATION, OF WILMINGTON, DELAWARE, A CORPORATION OF DELAWARE.

METHOD OF REFINING PETROLEUM OIL.

No Drawing.

Application filed December 17, 1924. Serial No. 756,560.

This invention relates to improvements in a process and method for refining petroleum hydrocarbons, and refers more particularly to the refining of oils in order to produce a pure, water-white distillate from which have been removed such objectionable properties as sulphur, gum, coloring matter and the like. More specifically, the method relates to the treatment of crude, unrefined, relatively heavy hydrocarbons used for the production of gasoline or other light hydrocarbon materials by pressure distillation or cracking.

The novelty in the present invention lies primarily in the treatment of hydrocarbons utilized as the charging stock to cracking systems prior to the introduction of such oils to the cracking process; the treatment consisting of subjecting the oil to an acid 20 treat and with or without water washing the same before cracking and subsequently subjecting the distillate obtained to a filtering action with an adsorbent material such as fuller's earth, aluminum silicate either treated or otherwise, which have the properties of removing certain objectionable matter from the oil.

In the production of gasoline by cracking certain types of petroleum, the resulting 30 product contains a large amount of sulphur and coloring matter. For example, in the cracking of gas oil made from California petroleum, the raw gasoline commonly contains as much as 0.75% sulphur. In the treatment of this gasoline with sodium 35 plumbite, or a solution of litharge in caustic soda, about 0.10% sulphur is removed, or by treatment with copper treated clay by any of the ordinary methods such as that 40 explained in a Patent No. 1,515,733 issued to me on November 18, 1924, the sulphur can further be reduced.

One of the most successful methods for removing sulphur is that of treatment with 45 strong or concentrated sulphuric acid. This, however, has the disadvantage that it causes polymerization and the gasoline produced has higher gum forming properties than before treatment. In the present cracking 50 process, using the high sulphur oils of California and Mexico, an end point gasoline is

produced without treatment or rerunning, but merely by the control and regulation of the temperatures and pressures and proper fractionation with a regulated control of the 55 overhead temperature. This gasoline complies with all of the standard requirements for motor gasoline such as color, distillation range, gum formation, copper corrosion and doctor test. However, it has been difficult 60 heretofore to treat this gasoline so that it contains less than 0.10% of sulphur without the use of large quantities of sulphuric acid followed by washing and distillation. The sulphur in gasoline and petroleum exists 65 substantially in the various forms as follows:

1. Free sulphur is found in certain Russian and Roumanian oils as well as in oils such as those from Luling, Texas, and certain parts of California and Montana. The sulphur in this form is ordinarily removed by sodium plumbite, particularly in the presence of mercaptan sulphur. It is also affected by copper treatment.

2. Hydrogen sulphide is commonly found in high sulphur petroleum and is often associated with free sulphur. In fact, free sulphur is often produced by the oxidation of hydrogen sulphide. Hydrogen sulphide 80 is readily removed by the action of sodium plumbite with which it forms lead sulphide. It can also be removed by washing with caustic soda or alkalies. A considerable amount of hydrogen sulphide is produced 85 from other compounds in petroleum when undergoing cracking. The removal of hydrogen sulphide in oil is therefore very simple.

3. Mercaptans. These are known as alkyl 90 hydrosulphides or thioalcohols having the general formula of RSH . With sodium plumbite they form lead mercaptides and lead sulphide, the latter in the presence of a small amount of free sulphur. They also 95 are precipitated as mercaptides with other metals such as copper, mercury and silver. Oxidizing agents convert them into soluble disulphides. They are soluble in concentrated sulphuric acid.

4. Alkyl sulphides (R_2S) are soluble in concentrated sulphuric acid and are not af-

fected by ordinary metals or oxidizing agents when cold.

5. Alkyl disulphide (RS_2) dissolve in sulphuric acid and are not affected by ordinary metallic salts or oxidizing agents when cold.

6. Thiophene (C_4H_4S) and related compounds are soluble in concentrated sulphuric acid and are not affected by metallic salts or oxidizing agents when cold and are decomposed with difficulty with copper compounds when hot.

7. Thiophanes (tetra-hydrothiophenes) ($C_nH_{2n}S$) are affected by oxidizing agents such as hydrochlorite and alkyl permanganates to form sulphones ($C_nH_{2n}SO_2$). They are oxidized and dissolved by concentrated sulphuric acid.

8. Sulphones are readily soluble in sulphuric acid but are not effectively treated with metallic salts.

9. Carbon bisulphide may be treated with oxidizing agents such as sodium hypochlorite most effectively to form sodium sulphate.

25. 10. Sulfoxides (RSO) dissolve readily in sulphuric acid.

11. Sulphonic acids are removed by concentrated sulphuric acid in the absence of water and are removed with difficulty by means of metallic salts. Sulphur dioxide is commonly formed from them in such treatment or by heating.

12. Sulphur dioxide is soluble in sulphuric acid and is removed by sodium plumbite and by oxidizing agents such as hypochlorite and permanganate.

It will be noted from the above that sulphuric acid is a very effective material for the removal of the sulphur bearing compounds but, as has already been pointed out, it has a rather serious drawback in that it produces polymerized gummy substances in the oil. In most instances, as has been pointed out in my Patent No. 1,515,733 issued 45 November 18th, 1924, copper treated clay will sufficiently completely remove sulphur under conditions of high pressure and temperature without the formation of gum and without increasing the end point or in any 50 way disturbing the boiling point range of the material. The cost of this treatment, however, when the percentage of sulphur is very high, is often excessive, as two pounds or more of copper is required for each pound

55 of sulphur to be removed. In the case of one percent sulphur in an oil of approximately three pounds per barrel, at least six pounds of copper will be required. Treatment of oil of this character would therefore be relatively expensive, even though the copper be recovered and reused over and over. Sulphuric acid, on the other hand, is an ideal substance for treatment as it is cheap and exists as a liquid. Also, it can be contacted 60 with the oil very inexpensively and the

acid may be recovered at a very small expense.

A typical example of the application of the process covered by the present invention would therefore be as follows: Gas oil, such as is produced by the coking distillation or the distillation to asphalt of Mexican or California crude petroleum, is first treated with a sodium plumbite solution in sufficient quantities to bring down practically all of the sulphur in the form of hydrogen sulphide and mercaptans as well as free sulphur. For this treatment, the treating solution is preferably warm. The gas oil is now washed with alkaline chlorinated water and after the water has settled, very rapidly treated with from ten to thirty pounds of 70 $66^{\circ} Bé$. sulphuric acid. This acid may be allowed to settle thoroughly, or may be treated with about a pound of clay to the 75 barrel and filtered to remove the last traces of sludge. It is desirable that water is not added until the sludge has been fairly completely removed; otherwise, the sulphuric acid compounds become redissolved in the 80 oil. The oil is then preferably treated with lime in a quantity sufficient to counteract the effect of any residual acid remaining in the oil. The oil is then adaptable for use as a charging stock in a cracking system. 85 Subsequent to cracking, gasoline of approximately water-white color and containing not more than 0.10% of sulphur under normal conditions, may ordinarily be obtained. This gasoline is then treated with sodium 90 plumbite and clay or may be treated very lightly and quickly with an exposure of not greater than thirty seconds to acid, followed immediately by a clay treatment and filtered in accordance with my copending application Serial No. 734,735 filed August 28th, 1924, and the application of Walter M. Cross, Serial No. 751,849 filed November 100 the 24th, 1924, in order to remove any of the treating substance remaining in the oil. 105

The whole treatment of the gas oil outlined may be accomplished in the ordinary continuous agitator according to well established methods for this purpose, the acid being contacted with the oil on the counter-flow principle, the oldest being in contact with the rawest oil and the new acid being in contact with the more thoroughly treated oil.

A typical result of this method of treatment is shown by the following sulphur contents at different stages:

	Per cent sulphur.
1. Raw oil	2.75
2. Oil treated with doctor solution	2.50
3. Oil treated with sulphuric acid	0.35
4. Synthetic crude oil	0.30
5. Raw cracked gasoline	0.12
6. Gasoline treated with sodium plumbite and filtered	0.05

The same raw oil, cracked without preliminary treatment, gave the following results:

	Per cent sulphur.
5 1. Raw oil.....	2.75
5 5. Raw gasoline.....	0.70
6 6. Gasoline after treatment with sodium plumbite.....	0.60

- 10 The process described, in which the charging stock to be converted in a cracking system is preliminarily treated with acid as described produced losses not in excess of 5%, and effectively eliminated polymerization more or less present to an objectionable extent where the final distillate is acid treated. The treatment described also eliminates the objection of throwing off the boiling range and end point of the product. Any 20 polymerization which takes place by acid in an original charging stock is not objectionable, as the range of boiling points in the distillation is reestablished during the cracking operation. Another advantage of 25 the process, and also a peculiarity, is the fact where the oil is given a preliminary treatment with acid as described, the yield is increased when the oil is cracked. For example, a treated gas oil low in sulphur, 30 yielded, after cracking, 34% of 437° F. end point gasoline; while the same gas oil, which had not been preliminarily treated, after being subjected to identical cracking condi-

tions, produced only 27% of 437° F. end point gasoline which had a high content of 35 sulphur, in contrast with the low sulphur content of the gasoline produced from the treating charging stock.

I claim as my invention:

1. A process of producing refined gasoline, 40 which consists in preliminarily treating a hydrocarbon charging stock suitable for cracking in successive steps with a sodium plumbite solution and with sulphuric acid, and subjecting the oil to a cracking action 45 for separating out the gasoline content.

2. A process of producing refined gasoline, 50 which consists in preliminarily treating a hydrocarbon charging stock suitable for cracking in successive steps with a sodium plumbite solution and with sulphuric acid, removing the treating materials from the oil neutralizing the acid treated oil and subjecting the oil to a cracking action for separating out the gasoline content. 55

3. A process of producing refined gasoline, 60 which consists in preliminarily treating hydrocarbon charging stock suitable for cracking in successive steps with a sodium plumbite solution and sulphuric acid, with an intermediate washing step of alkaline chlorinated water, neutralizing the acid treated oil and subjecting the oil to a cracking action for separating out the gasoline content. 65

ROY CROSS.
